UNITED STATES PATENT OFFICE.

ARTHUR W. CLAUSEN, OF CHICAGO, ILLINOIS.

CAR-COUPING.

1,360,268.

Specification of Letters Patent. Patented Nov. 30, 1920.

Application filed February 26, 1917. Serial No. 150,972.

To all whom it may concern:

Be it known that I, ARTHUR W. CLAUSEN, a citizen of the United States, and resident of Chicago, in the county of Cook and State 5 of Illinois, have invented certain new and useful Improvements in Car-Couplings, of which the following is a specification.

My invention relates to couplings for cars and has particular reference to a novel link 10 and pin coupling for narrow gage cars, such as ladle, mold or mine cars.

It will be understood that in the use of ladle and mold cars, it is undesirable to provide any coupling device which shall 15 require operation from the top, that is, in which there shall be an opening through the top wall of the sill or housing for the coupling device. This for the reason that metal, slag or cinder may be spilled and seriously 20 interfere with the operation of any coupling device having such vertical opening. It is furthermore desirable, and in fact necessary in the event of the employment of a bottom operating device, to provide operating means 25 which may be actuated from the side of the car.

I am aware that certain devices having this function have been proposed, the means herein shown and described having material 30 advantages thereover. One of the important advantages is in that all the operating parts of my device are mounted beneath a projecting ledge or shelf where they are not likely to become damaged due to 35 rough handling of the cars or their effectiveness to be impaired by the spilling of hot metal thereon. A further advantage is in that my operating device may be set or fixed in an open position of the coupler by the use 40 of but one of the operator's hands; that is by throwing a single lever the locking pin may be disengaged and retained in such position.

The invention will be more readily understood by reference to the accompanying drawing in which,

Figure 1 is a bottom plan view of the ends of two cars, each of which is equipped with coupling apparatus constructed in accordance with my invention:

Fig. 2 is an end elevation of one of the coupling devices and,

Fig. 3 is a sectional view taken on the line 3—3 of Fig. 1.

Referring more particularly to the drawings, it will be seen that to the ends of cars

such as indicated at 10, are secured massive castings which serve as the housings for the coupling apparatus and the operating means therefor. Each of these castings is provided with a top wall 11, a back or vertical wall 12, and a depending front wall 13. A horizontal recess or pocket 14, is formed in the front wall, the opening being tapered, as best shown in Figs. 1 and 2. A link, 65 which may be in the form of a flat bar 15, having openings, 16, in its ends, is adapted to be seated in these recesses, one end of the bar being adapted to be accommodated in the pockets of each of cars to be coupled. A 70 vertical pin 17, having an inclined upper end 18, serves to retain the link or bar in locked position. The pin is inserted vertically through an opening 20, in the lower wall 19, of the casting. Projecting downwardly from the bottom wall 19, are two pairs of apertured lugs or ears 21, 22. Pin operating levers 23, 24, are pivoted in the lugs, one arm of each lever being secured in the locking pin by means of the short 75 transverse pin or bolt 25. The outer ends of the levers 23, 24, are angularly bent, as best shown in Fig. 2, and terminate in handles 26, 27. The levers in their oscillation are guided between the back wall 12, 80 and a link 28, fixed to the back wall by pins or rivets 29, 30.

Also pivoted on the pin 30, is a bell-crank which acts as a trigger and serves to retain the pin-operating lever in uncoupling 90 position. One arm 31, of the bell crank acts as a handle to be manually grasped by the operator, while the other arm 32, is adapted to coöperate with a notch 33, formed in the lever. The position of the parts when the 95 arm 32, coöperates with the notch 33, is shown in dotted lines in Fig. 2. From that figure it will be seen that by grasping the handle 31, and rotating the bell-crank, the lever is caused to be moved on its pivot and 100 the locking pin to be lowered. When the parts have reached their limit of movement the arm 32, will be in engagement with the notch in the lever in which position they will be retained until the operator grasps the 105 handle 27, and lifts the lever sufficiently to permit the disengagement of the bell-crank therefrom and its restoration by gravity to the position shown in Fig. 2. The lever will then be released and the pin will be raised, 110 due to the greater weight of material on the outside of the pivot of the lever. If, how-

ever, the operator wishes merely to move the pin to unlocking position and not to retain the same in that position he will lift on the handle 27, thereby lowering the pin. After 5 the cars have been pulled apart the lever may be released when it will drop to the locking position.

It will be noted that all the operating parts are protected beneath the overhanging 10 top wall 11, of the casting and therefore are not likely to become damaged. Furthermore that the lock may be placed in lock-set position by one of the operator's hands, if necessary; that is, it is necessary only to grasp 15 and rotate the bell-crank to accomplish this result.

Obviously the exact form and arrangement 20 of the parts is not essential and I do not wish to be limited except as indicated in the appended claims.

I claim:

1. In a car coupler, the combination of a pocket member, an upright locking pin working through the bottom of the pocket member, 25 an uncoupling lever fulcrumed between its ends and extending transversely with respect to a car, one end of the lever being associated with the locking pin and the other end of the lever being free and accessible and constituting 30 an operating handle, and a bell crank locking lever mounted independently of said uncoupling lever, one arm of the bell crank lever constituting a handle and the other arm constituting a dog in co-operative relation 35 with the uncoupling lever for moving the same, the uncoupling lever having a seat to receive the dog arm of the locking lever to hold the latter in one position thereof.

2. Uncoupling mechanism for car couplers, 40 comprising an uncoupling lever fulcrumed intermediate its ends and having one end free and accessible and constituting a handle, the underside of the lever being provided with a seat, and a bell crank locking lever 45 having one arm constituting a handle and the other arm constituting a dog in wiping relation with the underside of the uncoupling lever for manipulating the latter by movement of the locking lever, the seat in the uncoupling lever being disposed to receive the 50 free end of the dog to lock the uncoupling lever.

3. In uncoupling mechanism for car couplers, the combination of a vertically 55 swinging uncoupling lever fulcrumed intermediate of its ends, one end portion of the lever constituting a handle and lying in a higher plane than that of the other end portion of the lever, said handle portion of 60 the lever having a seat in the under side thereof, and a bell crank locking lever fulcrumed below the handle end portion of the uncoupling lever and having one arm constituting a handle and the other arm constituting a dog, said dog being disposed in wiping 65

relation with the underside of the handle end of the uncoupling lever, and the seat in the uncoupling lever being disposed to receive the free end of the dog in an upright position thereof for locking the uncoupling 70 lever.

4. In a car coupler, a casting including a body having a substantially horizontal pocket opening through the front thereof and provided with a horizontal shelf extending in opposite directions at the top of the casting, front and rear flanges depending from the shelf and projecting at opposite sides of the body, a locking pin working through the bottom of the body and into the pocket thereof, a vertically rocking uncoupling lever fulcrumed intermediate of its ends upon the bottom of the body and having its inner end associated with the locking pin and its opposite end constituting a 80 handle lying beneath the shelf and accessible beneath one end thereof, the depending flanges constituting guards for the lever.

5. In a car coupler the combination of a casting including a body having a pocket 90 opening through the front thereof, a horizontal shelf at the top of the body and extending in opposite directions therefrom, front and rear flanges depending from the shelf at opposite sides of the body, a locking 95 pin working through the bottom of the pocket, an uncoupling lever fulcrumed between its ends upon a bracket depending from the body, the inner end of the lever being associated with the locking pin, the outer end of the lever being disposed above the inner portion of the lever and lying between the adjacent front and rear flanges and constituting a handle, and a locking bell 100 crank lever hung from the casting and fulcrumed below the handle portion of the uncoupling lever and having one arm constituting a dog in wiping relation with the underside of the handle portion of the uncoupling lever, said uncoupling lever having 110 a seat disposed for engagement by the dog in an upright position thereof to lock the uncoupling lever.

6. A car coupler pocket comprising a casting including a body having a pocket opening, the bottom of the pocket having an upright opening to receive a locking pin, shelf portions extending in opposite directions at the top of the body transversely with respect to the pocket opening, and front and rear flanges depending from the shelf and disposed at opposite sides of the body.

7. A car coupler pocket comprising a casting including a body having a pocket opening, the bottom of the pocket having an upright opening to receive a locking pin, shelf portions extending in opposite directions at the top of the body transversely with respect to the pocket opening, and front and rear flanges depending from the shelf and dis- 130

posed at opposite sides of the body, the body being provided with bolt openings extending therethrough from front to rear and at opposite sides of the pocket opening.

- 5 8. A car coupler pocket comprising a casting including a body having a pocket opening, the bottom of the pocket having an upright opening to receive a locking pin, shelf portions extending in opposite directions at 10 the top of the body transversely with respect to the pocket opening, and front and rear flanges depending from the shelf and disposed at opposite sides of the body, a coupling pin working through the opening in the bottom of the pocket, a vertically swinging uncoupling lever having an inner portion fulcrumed upon the bottom of the body and associated with the locking pin, the

outer portion of the lever being disposed at a higher elevation than the inner portion 20 and also located between the front and rear flanges, the outer extremity of the lever constituting a handle, and a bell crank locking lever fulcrumed between the flanges and below the upper portion of the unlocking lever 25 and having an arm in wiping relation with the under side of the unlocking lever and constituting a dog to lock the unlocking lever in an upright position of the dog.

Signed at Chicago, Illinois, this 22nd day 30 of Febr., 1917.

ARTHUR W. CLAUSEN.
